UNITED STATES PATENT OFFICE

157,766

HOMOGENIZING BOWL

Abraham S. Levin, Philadelphia, Pa.

Application September 28, 1948, Serial No. 148,801

Term of patent 7 years

(Cl. D23—1)

To all whom it may concern:

Be it known that I, Abraham S. Levin, a citizen of the United States of America, residing at Philadelphia, county of Philadelphia, State of Pennsylvania, have invented a new, original, and ornamental Design for a Homogenizing Bowl, of which the following is a specification, reference being had to the accompanying drawing, forming part thereof.

Fig. 1 is a perspective view of a homogenizing bowl, showing my new design.

Fig. 2 is a top plan view of the same.

I claim:

The ornamental design for a homogenizing bowl, as shown.

ABRAHAM S. LEVIN.
